UNITED STATES PATENT OFFICE.

REGNIER EICKWORTH, OF DORTMUND, GERMANY.

OPEN-HEARTH FURNACE.

1,176,744.

Specification of Letters Patent. Patented Mar. 28, 1916.

Application filed June 8, 1915. Serial No. 32,834.

To all whom it may concern:

Be it known that I, REGNIER EICKWORTH, of 49 Kaiser-Wilhelm Allee, Dortmund, in the Kingdom of Prussia, German Empire,
5 civil engineer, have invented certain new and useful Improvements in Open-Hearth Furnaces, of which the following is a specification.

My invention relates to open hearth furnaces and its particular object is to provide an arrangement for lengthening the life of the furnace ends which are known to be exposed to early destruction by the action of the hot gases on the exhaust end.

15 According to my invention channels connected with a compressed air conduit are arranged in the crowns of the furnace ends. The compressed air passing from the conduit into the channels exerts a cooling action 20 upon the crown even before passing around the crown into the exhaust channels where their cooling effect is greatest. However, as it is undesirable to feed cold air into the inlet end on account of the inevitable chilling 25 of the metal resulting therefrom, the compressed air conduit is provided with a reversing gear actuated together with the reversing gear of the furnace so as to cause a greater quantity of compressed air to pass 30 through the exhaust end whereas the inlet end receives little or no cooling air at all. The air reversing gear is preferably coupled with the furnace reversing gear.

In the drawings accompanying this specification a preferred form of an arrangement according to my invention is shown as adapted to an open hearth furnace of well known construction.

Figure 1 is a vertical longitudinal section, Fig. 2 is a horizontal longitudinal section, of a furnace embodying the invention on line 2-2 of Fig. 3. Fig. 3 is a vertical cross section on line 3-3 of Fig. 2.

a and *b* are the gas flues of the furnace. 45 *c* and *d* are compressed air channels arranged above the gas flues.

i, *k*, *l* are compressed air channels arranged in the crown of the furnace at opposite ends thereof above the combustion 50 channels *c*, *f*, *g*, *h* on both sides of the gas flues. These combustion channels have downward vertical extensions *e*, *f*, *g*, *h* at their outer ends.

All the air channels are connected to a compressed air conduit consisting of a main pipe *n* and two branch pipes *o* and *p*, each end of the furnace being thus provided with a compressed air conduit of its own. A reversing valve *q* of any well known construction inserted between the branch conduits *o* and *p* serves for governing the air feed to one or the other furnace end. By actuating the reversing valve accordingly either no compressed air at all is allowed to pass through the gas inlet channel, or the quantity of air admitted is kept low enough to cool the crown without impairing the quality of the metal on the hearth *r*.

The compressed air reversing gear *q* may be of any suitable type such as an ordinary valve or slide, a double valve, a three way cock and so on.

In the position of parts assumed in Fig. 1 the exhaust is on the left hand side. The gas enters through flue *b*, the regenerated air through channels *g* and *h*. The valve *q* is adjusted in such a position as to allow the compressed air from the main pipe *n* to pass only into the branch conduit *o* and from there through the exhaust end channel *c* into the exhaust flue *a*. The air passing through the side channels *i* and *k* cools the brick work covering the channels *e* and *f* thence passes through the apertures provided at the end of the air channels into the furnace and leaves the latter through the channels *c* and *f* which serve as supplementary exhausts. The parts of the exhaust end of the furnace are thus cooled by the air currents passing through said compressed air channels, while the metal in the hearth is not affected thereby. When the current of the furnace is reversed, as is usual in this class of furnaces, the inlet end becoming the exhaust end and the exhaust end the inlet end, the valve *q* is reversed and the compressed air current is cut off from the pipe *o* leading into the left hand end of the furnace and permitted to flow through the pipe *p* to the air channels at the right hand end of the furnace.

I claim:

An open hearth furnace having a hearth, flues at opposite ends thereof adapted to serve alternately as fuel supply and exhaust flues, combustion channels disposed in the

crown of the furnace and connected with
said flues, compressed-air cooling channels
disposed in said crown over said channels
and connected therewith for discharge
5 thereinto, and means for supplying com-
pressed-air to said cooling channels.

In testimony, that I claim the foregoing

as my invention I have signed my name in
presence of two subscribing witnesses.

REGNIER EICKWORTH. [L.S.]
